UNITED STATES PATENT OFFICE.

CHARLES E. ROGERS, OF DETROIT, MICHIGAN.

METHOD OF PACKAGING ICE CREAM.

Application filed December 3, 1921. Serial No. 519,724.

To all whom it may concern:

Be it known that I, CHARLES E. ROGERS, a citizen of the United States, residing at Detroit, county of Wayne, State of Michigan, have invented certain new and useful Improvements in Methods of Packaging Ice Cream, and declare the following to be a full, clear, and exact description of the same, such as will enable others skilled in the art to which it pertains to make and use the same, reference being had to the accompanying drawings, which form a part of this specification.

This invention relates to the packaging of ice cream, and the principal object of the invention is to provide a machine automatic in operation for the packaging of cream including a special form of package and the method of packaging ice cream. More particularly the invention involves a method and means for packaging ice cream in individual containers in which it is sold to consumers. Heretofore ice cream has been packaged in the form of quart or pint bricks, and the machine herein shown and mechanism for making a brick of several layers or colors is described in a co-pending application, this invention more particularly relating to the package and the method of packaging cream in layers in which the brick is made up of a plurality of individual containers or receptacles each filled with ice cream in the layer form. Heretofore it has been the practice with manufacturers of ice cream to wrap small portions or slices of ice cream for individual consumption in waxed paper in which it is sold to the consumer but the slicing and wrapping of these portions is costly ordinarily involving an expense of about twenty cents per gallon, and the object of this invention is to provide a mechanism and a method of packaging whereby portions corresponding to the individual portions heretofore made up by hand are automatically prepared by the machine herewith described without any hand operation being required. A further particular object of this invention is to provide a way and means for packaging individual portions of ice cream in layer form by automatic mechanism thereby avoiding the handling of ice cream and possible contamination thereof and permitting delivery of the same to the ultimate consumer in the original package and in wrapped portions of a size adapted for individual consump-

tion. These several objects and general means and apparatus required to secure the objects of the invention are shown in the accompanying drawings in which—

Fig. 1 is a side elevation of an ice cream packaging machine.

Fig. 2 is a plan view thereof.

Fig. 3 is a detail in perspective showing the method of bringing the packages to the filling device.

Fig. 4 is a perspective view of one form of package or container.

Fig. 5 is a longitudinal section thereof showing the method of stacking the individual receptacles in relation for the filling operation.

Fig. 6 is a detail showing the discharge aperture through which the packages are filled.

Figs. 7, 8 and 9 show other forms of package adaptable for use in my improved method of packaging.

Ice cream to be packaged with this machine must be in a semi-fluid or semi-frozen condition and packaged in such semi-frozen condition and then hardened in the original package previous to sale to the consumer. The machine, so far as the package and method of packaging is concerned, may be of various types, an essential part of the machine for packaging ice cream in layers, however, being a series of containers each having an aperture and the several apertures being in alignment through which the ice cream may flow into the package. The general operation of the machine is set forth in the said co-pending application and the machine is herein shown in Fig. 1 in side elevation. The preferable machine consists generally of a frame or base 1 and mounted thereabove are the containers which are preferably annular in form and in concentric relation as will be understood particularly from Figs. 3 and 6. These containers 2, 3 and 4 are preferably formed of sheet metal, the walls of which are converging toward the lower end as shown in Fig. 6, and on diametrically opposite sides of the containers are groups of apertures 5, 6 and 7 in horizontal alignment and of rectangular form, the outline of the several apertures being approximately that of the rectangular receptacle 8 shown in Figs. 3 and 4. Mounted on the upper surface 1^a of the base 1 are raceways 9 and 10 on the opposite sides as will be understood from Fig. 2. A central

shaft 11 is provided operated by a motor (not here shown) and this shaft extends upward centrally of the several containers and is provided with arms 12 on which are depending arms 13, 14 and 15 for the respective containers which are revolved therein to maintain the semi-solid ice cream in a state of uniform consistency and also to carry the ice cream, as the containers become emptied, to the aligned apertures through which it is discharged by gravity into the receptacles. The boxes or receptacles to be filled are of the usual paraffined cardboard type and are moved longitudinally of the raceways step by step bringing the receptacles to filling position consecutively. The boxes are moved consecutively to filling position by means of a cam 16 on the shaft 11 such as is described in the said co-pending application and this cam simultaneously reciprocates a follower 17 in the raceway 9 and the follower 18 in the raceway 10. The packages are placed forward of this follower and each forward movement (which is to the right of the position shown in Fig. 1) moves exactly the length of the box and these boxes between the follower and the box being filled push the filled box from the aperture and positions the succeeding box for filling, it being understood that the periphery of the rectangular box 8 is in sealed relation about the periphery of the apertures as will be understood from Fig. 6. The filled boxes are moved out from the machine onto a table 19 at the rear side thereof. It will be understood from Fig. 6 that the ice cream flows into the packages in multiple layer form, in the device here shown there being three layers, but any number of layers may be provided as may be found practicable depending upon the size of the package to be filled. It is to be noted that these packages are fed longitudinally through the machine, and on the opposite sides of the machine in the special form of machine here shown, and the apertures extend longitudinally of the boxes so that the layers of ice cream are placed in the package through the upper open side of the box and the layers extend longitudinally of the box or receptacle.

To package the ice cream in individual wrapped slices or portions for individual consumption I provide a special form of receptacle which consists of the outer supporting receptacle 8 in which are placed a series of individual receptacles, there being six or eight of these individual receptacles for use in a quart size receptacle 8 corresponding to the usual size now wrapped in waxed paper by the manufacturers. These individual inserts 20 are of the paraffined paper or cardboard type and are held in close relation by the outer box 8 as shown in Figs. 4 and 5 from which it will be understood

that the inserts are held sufficiently close together as to prevent ice cream from flowing therebetween. A particular feature of these open individual containers 20 is that they extend transversely of the box 8 and of the aligned apertures 5, 6 and 7 of the containers when in filling position and it is to be noted that as the ice cream flows downward each individual receptacle 20 receives the ice cream in layer form. In some devices for packaging ice cream in layer form as for instance in the device shown by U. S. Patent to Cuscaden et al., No. 682,243 of Sept. 10, 1901, dividing plates are utilized which are moved downward into the receptacle to be filled in order to provide the layer form of the ice cream in the package. I have found that particularly with the package containing the individual receptacles, the dividing plates may be dispensed with, permitting the ice cream to flow preferably without subjection to pressure through the several apertures which will deposit in these individual receptacles (which are held in position by the outer box 8) in practically perfect layer form without intermingling of the colors or flavors discharged from the different containers and this is one of the features necessary in the performing of my new method of packaging—that is, that the ice cream is discharged through the aligned apertures simultaneously into these individual receptacles which extend transversely of the aligned apertures whereby each individual receptacle receives ice cream in the several layers.

Heretofore, in the making of the slices or portions for individual consumption, the slices are cut from the hardened brick and then wrapped by hand and then packed in a container. The object of my improved method is to avoid the hand work and possible contamination as well as the labor and to deliver the ice cream in the individual package to the ultimate consumer and this is only possible by my method herein described in which the ice cream is deposited, in the semi-fluid or semi-frozen condition in which it is discharged from the freezer, in the original package in which it is to be sold to the consumer and then hardened previous to its sale. This is believed a new and important step in the art resulting in a lessened cost as before stated and the maintenance of the purity of the product sold.

Manifestly the individual containers 20 are not necessarily of the exact shape or structure shown in Fig. 4 or 5, an alternate form being shown in Fig. 8 in which the individual container 30, of the same shape as the container 20, has one end thereof 31 formed with perforations 32. This end 31 may be stripped or torn from the body of the package to permit the ready discharge of the ice cream contained or for holding

in the hand by the remainder of the package permitting the ice cream to be carried in the hand and eaten as is sometimes done where the ice cream is used by picnicing parties or assemblages where the ordinary table service is not provided. The essential feature, however, of whatever form of individual containers is used is that it shall have an open end and adapted to be positioned in an outer container of some character to support the individual containers in close relation during the filling operation and to hold them intact during the hardening operation after which they may be separated from the outer container if desired previous to sale. It is to be understood however, that after the hardening operation, the packages should be provided with some character of closure for covering the open ends of the individual packages.

It is believed essential that the outer supporting box 8 shall have the edge thereof sealed to the periphery of the discharge aperture of the containers to prevent ice cream from flowing to the outside of the box for this purpose and, as described in said co-pending application, the raceway is provided, at a point beneath the aperture of the containers, with an adjustable table which is adjusted by means of the bolts and nuts 40 shown in side elevation in Fig. 1. This adjusts the vertical position of a portion of the bottom of the raceway to carry the box on the said portion to close contact with the bottom of the containers about the apertures and guides 41 are provided parallel with the raceway so that the box is positioned correctly relative to the apertures.

The follower member is actuated by a rod 42 which is adjustable to vary the position of the follower 17 or 18 so that each forward movement thereof is exactly of the length required to move the filled box from position and deposit an unfilled box for the filling operation.

It is considered essential in the performance of this method of packaging that the ice cream shall be in a semi-frozen condition as discharged from the ice cream freezer, the several containers being filled in any approved way with ice cream of different color or character so that the individual package is formed of a number of layers of differently colored ice cream or ices of a different character.

The foregoing description particularly sets forth the filling of the packages in layers but it is evident that the method is applicable whether the ice cream is to be deposited in layers or in uniform color or character. For this latter purpose, if the several concentric containers are to be used, the containers should all be filled with ice cream of the same character and color which will flow readily into the boxes as heretofore

described, or if desired a single container may be used provided with a single aperture through which the ice cream is discharged, the aperture being practically of the same size as the outer box. Under this plan and 70 arrangement the individual receptacles 20 or 30 will each be filled with ice cream of the same color.

This method is particularly applicable where the ice cream is to be wrapped in 75 small parcels providing an amount for individual consumption as for instance with ice cream sodas and these may be rectangular in form as shown in Fig. 7 or of any desired shape, it being essential, however, that in this method the several individual receptacles or boxes shall be held in close relation side by side and end to end in an outer receptacle of some nature for the filling operation and preferably are retained 80 in this outer binder or receptacle during the final hardening. Fig. 9 shows a slightly different form of the inserted package 50 which has the two open ends 51 and 52. As these individual receptacles may be used 85 with an outer box (which is provided with a bottom), the individual containers may be of four sides only and the outer package will prevent the ice cream from flowing out 90 of the bottom of the inserted package 50. 95

The inner individual packages, which are formed of a waterproof paper as before stated and of whatever shape, may be of lighter weight and thinner wall than the outer sustaining package, the purpose of the outer package being to hold the individual receptacles in close relation with the walls in contact and prevent deformation of the smaller packages during the filling with ice cream and this outer box being of heavier 105 character is used both to sustain the boxes while being filled and to prevent deformation previous to or during the final hardening.

Ice cream to be palatable and of desired 110 texture should be filled with minute air cells which is accomplished by the comparatively rapid stirring of the material of which the ice cream is formed during the freezing and when in the semi-frozen condition is deposited in these containers 2, 3 and 4. When in the containers the semi-frozen ice cream is continuously agitated by the arms 13, 14 and 15 extending downward into the 115 containers and rotated therein. These 120 stirrers or agitators have the function of maintaining the ice cream in a state of uniform consistency which is essential to its flow by gravity into the packages. Without the stirrers or agitators the ice cream in the containers that lies in contact with the container wall would tend to melt to a greater or less extent leaving the body of ice cream 125 between the walls in a harder condition than that in contact with the walls. By use of 130

agitators the ice cream is maintained in uniform state and capable of flowing by gravity at all times and it is preferable that ice cream be deposited in order that the air cell structure may not be destroyed. A limited amount of pressure could be utilized, however, if found desirable. Pressure, however, tends to compact the ice cream which is an undesirable feature making it hard and 10 destroying its texture. Therefore deposition by gravity or by very little pressure, wherein the ice cream retains its air cell structure is the better method.

The foregoing description refers particularly to the packaging of ice cream in a semi-solid or semi-frozen condition. It is to be, however, understood that various materials may be packaged by my improved method as for instance, ices which are prepared in a semi-frozen condition and then hardened, gelatines for desserts which may be packaged while in a semi-fluid condition and then allowed to harden in the package, or cake dough or paste for pastry, the material for which is made up in a semi-fluid form which, while in such form may be packaged and then baked. All these different materials and other material of the same general characteristics may be readily 30 packaged by this method either in layers as

may be desired or in the mass by using a container having only a single aperture through which the material is discharged. The package in any case may be of the general form herein disclosed or without the individual inserts described herein and the appended claims are to be read with this understanding that various types of semi-fluids may be packaged by this method and then hardened for sale to the ultimate consumer in the original package.

Having thus fully described my invention, what I claim is—

1. The method of filling receptacles with different materials in strata which consists in spacing longitudinally of the receptacle within the same, a series of material enclosures designed ultimately to encompass an individual portion of the material and flowing the strata of materials into the enclosures.
2. The method of filling a receptacle with material consisting in spacing longitudinally of the same, a series of material enclosures designed to ultimately encompass an individual portion of the material, and flowing the material into the enclosures.

In testimony whereof, I sign this specification.

CHARLES E. ROGERS.
